UNITED STATES PATENT OFFICE

2,641,733

HIGH-FREQUENCY TUBE

Donald B. Harris and Ralph L. McCreary, Cedar Rapids, Iowa, assignors to Collins Radio Company, Cedar Rapids, Iowa, a corporation of Iowa

Application January 8, 1951, Serial No. 204,882

2 Claims. (Cl. 315—6)

1

This invention relates in general to electronic devices and in particular to ultra-high frequency tubes.

In the field of electronics, engineers have continuously pushed to higher frequencies for transmission of radiant energy. Reasons for this are that, due to the large number of transmitting stations more frequencies are needed for new transmitters and secondly, transmission at the higher frequencies is oftentimes accomplished with a minimum of interference caused by variations in the Heavyside layer and similar disturbing factors. One high frequency electronic device is the klystron, which has a bunching cavity through which an electron beam is passed and which bunches the electrons proportional to the frequency of the cavity. The electrons pass through a drift space where further bunching occurs and into an anode cavity which is resonant at the bunched frequency and thus driven by the electron stream. The output of the anode cavity is removed by a coupling loop. The disadvantages of the klystron are that the electron gun is never turned off and thus the cathode gives a constant output. This results in a relatively low efficiency and a theoretical maximum efficiency of 57%.

The resonatron is another high frequency electronic device which has a resonant circuit comprising the grid and the cathode. An anode is placed so as to intercept electrons passing from the cathode. The resonatron is constructed as a radial structure wherein a center cathode is surrounded by a concentric grid structure and an outer concentric plate. The grid controls the electron flow from the cathode and can cut it off so that the tube can be operated in class C fashion. This results in greatly increased efficiency. Due to the concentric arrangement of the resonatron tube, the size of the cathode is of necessity relatively small and the emission current is limited thereby.

It is an object of this invention, therefore, to provide an electronic device which may be operated in class C fashion by obtaining a high emission current from the cathode.

Yet another object of this invention is to provide an axially aligned electronic device which has a control grid forming part of the resonant cathode that will turn off the cathode during a part of the cycle.

Yet another object of this invention is to provide an improved highly efficient electronic device.

A feature of this invention is found in the provision for an anode and a cathode spaced in

5 axial alignment and with the cathode formed with a choke that divides it into two parts so that a control potential may be supplied to the non-emitting portion.

10 Further objects, features and advantages of this invention will become apparent from the following description and claims when read in view of the drawings, in which:

Figure 1 is a cut-away view of the electronic device of this invention; and

Figure 2 is a characteristic curve showing the relationship between grid bias and output.

Figure 1 illustrates an envelope or shell, designated generally as 10, in which is mounted an anode 11 which is generally cylindrically shaped. The upper wall 12 of the anode 11 is formed with a cone shaped portion 13 at its center and the opposite wall 14 is formed with a central opening 16. The anode 11 is supported from the envelope 10 by mechanical supports 17.

20 A cathode, designated generally as 18, is generally cylindrically shaped and is formed in two sections including an upper section 19 and a lower section 21. The lower section 21 has a bottom 22 and upwardly extending side walls 23. The bottom 22 is formed with a center cup-shaped extrusion 24. The upper section 19 is smaller in radius than the lower section 21 and has a top 26 and downwardly extending walls 21. The walls 27 fit concentrically within the walls 23. Resistive material as, for example, a thin layer of ceramic 28, is placed between the outer edge of wall 27 and the inner edge of wall 23. The material 28 thus insulates the member 19 from the member 21 for a direct current potential. For alternating frequencies, however, the material 28 offers very little impedance and thus it provides means for maintaining the member 19 at a direct current potential different from that of the member 21 while they are at the same high frequency potential. The cathode 18 is supported from the envelope 10 by the mechanical supports 20.

25 The cup-shaped portion 24 is coated on its inner surface with an emitting material 26 and a heater 25 heats the cup-shaped portion 24 to cause electron emission from the inner surface thereof.

An input loop 29 passes through the wall 22 and has its end connected to it. In the anode cavity 11 an output loop 31 passes through the wall 12 and connects to the inner wall.

30 A lead 32 is connected to the anode 11 and passes out through the wall of the envelope 10. A second lead 33 connects to the wall 21 of the

35

cathode and passes out through the wall of envelope 10. A lead 34 connects to the wall 27 of the cathode and passes through the side wall of the envelope. An accelerating direct current voltage E_b is connected between the leads 32 and 33 with the positive side connected to the lead 32. A direct current biasing voltage E_c is connected between the leads 34 and 33 with the negative side of the voltage connected to the lead 34.

In operation, the envelope 10 is evacuated and the heater 25 is connected to a heating voltage so as to raise the temperature of the cathode 24 high enough to cause electron emission from the material 26. The shape of the member 24 causes focusing of the electrons emitted from the inner surface and, providing that the correct bias is placed on the member 19, the electrons will pass through the cathode cavity and out the opening 36 formed in the wall 28. The electron stream will interact with the cathode cavity 18, and will be modulated by the resonant frequency of the cavity so that bunching will occur in the drift space between the opening 36 and opening 16. It may prove desirable to place an external magnetic field so as to pass flux between the cathode and anode and thus aid in focusing the electron beam.

The electrons enter the anode cavity through the opening 16 and impinge on the target 13. As they traverse the anode the bunched electrons excite and drive the anode cavity so that energy may be removed by the pick-off loop 31. The operation thus far described is similar to that of a klystron. Because of the insulation between the members 19 and 24 of the cathode, however, the electron beam may be turned off during a portion of the cycle so that the tube may be operated in class C fashion. This means that the electron beam is periodically interrupted so that greater efficiency may be obtained.

This is illustrated in Figure 2. The input exciting voltage supplied by the lead 29 is near the resonant frequency of the cavity 18 and the direct current voltage E_c placed on the lead 34 prevents the electron beam from passing out of the opening 36 except on the positive peaks of the exciting voltage. Thus, as shown in Figure 2, the electron beam emerges from the opening 36 only at times when it is above the biasing voltage, E_c . This results in the tube operating in class C fashion, thus greatly increasing the efficiency. Thus the electron stream will be turned on and off so that pulses will be released from the cathode cavity. These pulses will be received through the opening 16 in the anode which is tuned to substantially the same resonant frequency as the cathode and thus the pulses will excite oscillation of the anode cavity at a high energy level. The output loop 31 will remove

this energy. Since the tube is operated in class C fashion the emission of the cathode is not constant and thus a high level of emission is not constantly required.

The electrons which flow through the drift space between the cathode and anode tend to bunch due to the variable slope of the bias on the member 19. This increases the concentration of energy.

10 Although this invention has been described with respect to a preferred embodiment thereof, it is not to be so limited as changes and modifications may be made therein which are within the full intended scope of the invention as defined by the appended claims.

15 We claim:

1. A high frequency electronic device comprising, an evacuated envelope, an anode structure wholly within and supported by said envelope, 20 a cathode structure supported within said envelope in axial alignment with said anode, said anode comprising a relatively short hollow cylindrical member, one end wall of said hollow cylindrical member formed with a central opening, 25 said cathode comprising, a pair of discs with short peripheral flanges, the flange of one of said discs mounted telescopically within the flange of the other disc, said discs being spaced remote from each other, said flanges telescopically overlapping each other, and the first of said discs 30 formed with a central opening in axial alignment with said anode.

2. A high frequency electronic device comprising, an evacuated envelope, a hollow cylindrical 35 anode mounted within said envelope, a pair of end walls forming a part of said anode, the first end wall formed with a central opening, the other end wall formed with a central cone-shaped portion, a cathode mounted within said envelope,

40 said cathode comprising first and second discs with short peripheral flanges, the flange of one of said discs mounted telescopically within the flange of the other disc, said discs being spaced remote from each other, the first of said discs 45 formed with a central opening, the other disc depressed into a generally focusing cathode surface, a heater mounted adjacent the second disc behind the cathode surface, and the anode and cathode mounted in axial alignment so that a

50 stream of electrons emerging from the opening in said first disc will pass into the anode through the opening formed in the first end wall.
